CLAIM

The ornamental design for housing for a portable computing device, as shown and described.

DESCRIPTION

FIG. 1 is a perspective view of housing for a portable computing device showing our new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof; and,

FIG. 7 is a perspective view thereof shown in a usage state wherein the broken lines illustrate portions of the computing device and form no part of the claimed design.
